HOLDER FOR FISHING TACKLE AND THE LIKE

Harold C. Malcolm, 2945 NW. 87th Terrace, Miami, Fla.

Filed Dec. 2, 1964, Ser. No. 32,885

Term of patent 14 years

(Cl. D31—4)

FIGURE 1 is a top plan view of a holder for fishing tackle and the like, embodying my new design;

FIG. 2 is an edge elevational view looking down from the top of FIG. 1;

FIG. 3 is an edge elevational view looking to the left from the right hand side of FIG. 1;

FIG. 4 is a sectional view taken along the line 4—4 of FIG. 1, looking in the direction of the arrows; and

FIG. 5 is a sectional view taken along the line 5—5 of FIG. 1, looking in the direction of the arrows.

I claim:

The ornamental design for a holder for fishing tackle and the like, as shown.
